UNITED STATES PATENT OFFICE.

HENRY E. RUSSELL, JR., OF NEW BRITAIN, CONNECTICUT.

LOCK-BOLT.

SPECIFICATION forming part of Letters Patent No. 434,470, dated August 19, 1890.

Application filed July 7, 1890. Serial No. 357,992. (No model.)

To all whom it may concern:

Be it known that I, HENRY E. RUSSELL, Jr., a citizen of the United States, residing at New Britain, in the county of Hartford and State 5 of Connecticut, have invented certain new and useful Improvements in Lock-Bolts, of which the following is a specification.

My invention relates to improvements in lock-bolts; and the object of my improvement is simplicity and cheapness of construction, whereby a light and substantial lock-bolt is produced from sheet metal.

In the accompanying drawings, Figure 1 is a front elevation of the lower part of a combined latch and lock-case with locking mechanism having my lock-bolt applied thereto. Fig. 2 is a side elevation of the same, showing the face-plate and end of the lock-bolt. Fig. 3 is a detached front elevation of my lock-bolt. Fig. 4 illustrates the same with the head end in blank form, and Fig. 5 is an end view of my lock-bolt.

A designates the lock-bolt, and B the face-plate, of the combined latch and lock-case C. 25 The shank or body 6 of the lock-bolt is of the ordinary form, and so, also, are the other parts, with the exception of the head end of the lock-bolt and the mortises therefor in the face-plate.

30 The head end of my lock-bolt consists of a series of sheet-metal bars 7, extending longitudinally with the bolt, and in the finished

bolt having their width extended from front to rear, as shown. The mortises in the face-plate B consist of a like number of slots, to 35 which the several bars 7 are fitted. I form this head end from a flat sheet-metal blank, substantially such as is shown at the left-hand end of Fig. 4, the same being slit longitudinally on the lines 8 8 8 to divide the same 40 into the desired number of bars. These bars are then so twisted that their broad sides extend from front to rear, as shown in the other figures, thereby forming a bolt-head of sufficient strength and bulk, and one which may 45 be used with a keeper having the ordinary form of mortise.

While I have shown and described my improvement as embodied in a lock-bolt only; it is evident that the same construction may 50 be applied to analogous bolts—as, for instance, a mortise door-bolt and the like.

I claim as my invention—

The herein-described sheet-metal bolt, consisting of a body or shank 6 and a head composed of longitudinal sheet-metal bars 7, with 55 their broad sides extending from front to rear, substantially as described, and for the purpose specified.

HENRY E. RUSSELL, JR.
